UNITED STATES PATENT OFFICE.

JOHN CROZIER, OF STE. AGATHE, QUEBEC, CANADA.

RAILWAY-RAIL CHAIR.

No. 844,500.

Specification of Letters Patent.

Patented Feb. 19, 1907.

Application filed September 11, 1905. Serial No. 277,845.

To all whom it may concern:

Be it known that I, JOHN CROZIER, a subject of the King of England, residing at Ste. Agathe, in the county of Lotbiniere, Province of Quebec, Canada, have invented certain new and useful Improvements in Railway-Rail Chairs; and I do hereby declare that the following is a full, clear, and exact description of the invention, such as will enable others skilled in the art to which it appertains to make and use the same.

My invention relates to railway-rail joints.

The object of my invention is to provide a rail-chair which will form a solid support for the meeting ends of rails and prevent depression thereof by the weight of a train passing thereover.

A further object of my invention is to provide a simple and efficient locking means for binding the parts of my rail-chair together on a rail, so that the parts are firmly held against detachment; and my invention consists of the construction, combination, and arrangement of parts as herein illustrated, described, and claimed.

In the accompanying drawings, forming a part of this application, I have illustrated one form of embodiment of my invention, in which drawings similar reference characters designate corresponding parts, and in which—

Figure 1 is a side elevation showing the application of my invention to the abutting ends of two rails. Fig. 2 is a horizontal section taken approximately on line 2 2 of Fig.

3 3 of Fig. 1, and Fig. 4 is a vertical section taken approximately on line 4 4 of Fig. 2.

Referring to the drawings, 5 designates the tread, 6 the web, and 7 the base-flanges of a common form of railway-rail. To bind the ends of the abutting rails together, I provide a main member, having a base 8 which is of greater width than the base-flanges 7 of the rails to be bound. One side of this base 8 has a flange 9, which fits closely to the upper face of the flange 7 and the web 6 and terminates just below the bottom face of the tread

5. Adjacent the edge of the base 8, opposite the flange 9, said base is provided with a T-shaped channel or groove 10, in which is disposed a jaw having a T-shaped base 11 of approximately the same size and contour as the groove or channel 10. On the T-shaped

base 11 is a flange 12, which extends upward and inward to a point just below the under face of the tread 5 of the rail and closely fits that side of the rail, all as best shown in Fig. 3 of the drawings.

The flange 12 is provided with a plurality of slots 13, Figs. 1 and 2, through which are projected the fastening-bolts 14, the openings in the flange 9 being round. These bolts are provided with the usual rounded heads 15 and have their opposite ends provided with the screw-threads 16.

Longitudinally of the bolts and at their screw-threaded ends are provided a plurality of grooves 17 of approximately the same depth as the screw-threads 16. After the parts are adjusted to the proper position and the bolts 14 inserted the nuts 18 are placed on the bolts and tightened up in the usual way. Each of the nuts 18 is provided with an interior chamber 19, in which is loosely mounted a member 20, on the surface of which is provided a cam-surface having an edge 21, said cam-surface approximating the interior contour of the chamber 19. This edge 21 is adapted to engage the grooves 17 when the nuts are tightened up, so that a reverse movement of the nuts is prevented. When the nuts are being tightened up, the cam-surface of the member 20 is carried back into the chamber; but the nut is prevented from working loose because the edge 21, being engaged in one of the grooves 17, strikes against the edge of the chamber 19 and prevents further reverse movement of the bolt.

While I have shown in the accompanying drawings the preferred form of my invention, it will be understood that I do not limit myself to the precise form shown, for many of the details may be changed in form or position without affecting the operativeness or utility of my invention. I therefore reserve the right to make all such modifications as are included within the scope of the following claims or of mechanical equivalents to the structures set forth.

Having thus fully described my invention, what I claim as new, and desire to secure by Letters Patent, is—

1. A railway-rail chair comprising a base having a flange on one side and having a T-shaped groove on the opposite side thereof, a jaw having a T-shaped base disposed in said groove and having a flange extending from said base provided with slots therein, and

bolts projected through the flange of said first member and through the slots of said second member and nuts on the bolts provided with rockable locking means.

5 2. A railway-rail chair comprising a base having a flange on one side and a groove on its opposite side, a jaw having a base disposed in said groove and having a flange extending from the base, bolts connecting said flanges and provided with longitudinal grooves therein, nuts disposed on the bolts, and a rockable locking member carried by each of the nuts adapted to engage in said grooves.

3. A railway-rail chair comprising a base 15 having a flange on one side and a groove on its opposite side, a jaw having a base disposed in said groove and having a flange extending from its base, bolts connecting said flanges and provided with grooves therein, nuts disposed on the bolts and provided with a chamber therein, and a locking member rockably

disposed in said chamber and provided with a cam edge adapted to engage in said grooves.

4. The combination comprising a rail having a tread, a web and base-flanges; a member having a base disposed under said flanges, having a flange on one side of its base and having a groove on its opposite side; a jaw having a base disposed in said groove and having a flange extending from said base; 30 bolts disposed through said flanges and said web and provided with longitudinal grooves; nuts disposed on the bolts; and, a rockable locking member carried by the nuts adapted to engage said grooves. 35

In witness whereof I have hereunto set my hand in the presence of two witnesses.

JOHN CROZIER.
